UNITED STATES PATENT OFFICE.

FRANK S. GIBSON, OF GREENVILLE, MICHIGAN.

REFRIGERATOR CONSTRUCTION.

Application filed July 31, 1925. Serial No. 47,297.

The present invention relates to refrigerator construction and more particularly to means for finishing the doors and frames of refrigerators and providing sealing means 5 therefor.

Among the objects of the invention is to provide a simple, cheap, efficient and ornamental finish for door edges and frames and a finish that is easily and quickly applied.

10 Another object is an efficient air-tight seal for such doors.

Still other objects will be readily apparent to those skilled in the art upon reference to the following description and drawing, in 15 which—

The figure is a section through a part of a refrigerator wall and the adjacent edge portion of a door therefor.

In the drawing there is shown a section 20 of a refrigerator wall at 1 and of the edge of a refrigerator door at 2. The interior of these parts is of the usual construction, that is, they consist of a wooden outer wall portion 3 with an adjacent heat insulating 25 layer of cork board 4 having a sheet 5 of metal or other suitable material on each side thereof. In addition, the wall section is provided with an inside wood layer 6.

As is well known in refrigerator construction, 30 these parts may be covered with formed metal sheathing 7 which itself is covered with a thick layer of vitreous enamel.

The metal sheathing is first formed of the proper size and shape and the enamel applied in a process requiring a high heat. 35 This operation frequently causes the metal to become somewhat distorted and to vary from the intended dimensions. Consequently, it is difficult to prepare such sheathing 40 so that the edges will lie in the same relative position on two like bodies.

This objection is overcome in the present structure by using finishing strips which overlap the edges of the sheathing and are 45 secured thereto and to the body.

Such strips are preferably of aluminum and are indicated at 8, 9 and 10. The strip 8 is secured at the edge of the door and extends from over the edge of sheathing 7 to 50 somewhat beyond the edge of the door. The strip 9 overlies the edge of the inside sheathing 7 of the wall and extends about half

way from this edge to the edge of the outside sheathing, that is, to about the middle of the strip 14 against which the door edge 55 ordinarily abuts. The strip 10 extends from close to the edge of strip 9, where it lies on the step 14, to over the edge of the outside sheathing of the wall, it being understood that all of the strips will be secured by suitable means such as the screws 11.

In order to make an airtight seal of the door 2 on closing, there is inserted between the adjacent edges of strips 9 and 10 a packing strip which consists of a tubular part 12 65 having a longitudinal flange 13. The flange is inserted under the edge of strip 10 and secured therewith to the body by any suitable means, such as by tacks or screws. The tubular portion may be hollow but is preferably filled with a rubber strand cord, the outer cover being preferably also of rubber.

When the door is shut the packing strip will be compressed between the step 14 and the corresponding step 15 on the door and 75 make an airtight seal for the latter, it being understood that the construction shown extends entirely around the door opening.

The edge of inside sheathing 7 on the door is preferably flanged as shown at 16 and is 80 secured by finishing strips of molding 17, the latter being secured by screws or nails, not shown.

Having now described the invention and the preferred form of embodiment thereof, 85 it is to be understood that the said invention is not to be limited to the precise details as shown and described but only by the scope of the claims which follow.

I claim—

1. In refrigerator construction, a heat insulated wall body having a stepped door opening, metal sheathing on the inside of said body, metal sheathing on the outside of said body, the inside and outside sheathing having adjacent edges spaced apart, and finishing strips consisting of two adjoining strips of metal overlying said edges and covering the body therebetween, the adjoining edges of said strips lying on a step of said door opening, and a door gasket secured to said step longitudinal of said junction.

2. In refrigerator construction, a heat insulated wall body having a stepped door

opening, metal sheathing on the inside of said body, metal sheathing on the outside of said body, the inside and outside sheathing having adjacent edges spaced apart, and 5 finishing strips consisting of two adjoining strips of metal overlying said edges and covering the body therebetween, the adjoin- ing edges of said strips lying on a step of said door opening, and a door gasket secured to said step longitudinal of said junction, said gasket consisting of a gasket portion and a flange portion which latter is secured under one of said strips.

FRANK S. GIBSON.
